J. STRAUB

CUSPIDOR

Filed July 13, 1923

UNITED STATES PATENT OFFICE.

JOHN STRAUB, OF ASHLEY, NORTH DAKOTA.

CUSPIDOR.

Application filed July 13, 1923. Serial No. 651,348.

To all whom it may concern:

Be it known that I, JOHN STRAUB, a citizen of the United States, residing at Ashley, in the county of McIntosh and State of North Dakota, have invented certain new and useful Improvements in Cuspidors, of which the following is a specification.

This invention relates to cuspidors, designed primarily for use in connection with railway coaches and street cars, but it is to be understood that a cuspidor in accordance with this invention can be employed for any purposes wherein it is found applicable, and the invention has for its object 10 to provide in a manner as hereinafter set forth, a cuspidor including a shiftable bottom normally in closing position, of a valvular type, and capable of conveniently shifting to open position to provide for the discharge of the contents of the cuspidor without removing the latter from its set position.

A further object is to provide, in a manner as hereinafter set forth, a cuspidor including a hinged cover provided with means for detachably securing it in closure position with respect to the top of the body portion of the cuspidor.

Further objects of the invention are to provide a cuspidor, in a manner as hereinabove set forth, which is simple in its construction and arrangement, ornamental in appearance, strong, durable, compact, readily installed, thoroughly efficient and convenient in its use.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claim hereunto appended.

In the drawings wherein like reference characters denote corresponding parts throughout the several views:—

Figure 1 is a side elevation of a cuspidor in accordance with this invention.

Figure 2 is a vertical sectional view.

Figure 3 is a fragmentary view illustrating the cover in open position.

A cuspidor in accordance with this invention can be secured at any desirable point of the car or coach body so that the contents

of the cuspidor can be conveniently discharged when occasion so requires, and referring to the drawings in detail the cuspidor comprises a body portion formed of any suitable material, preferably of sheet metal, and which includes an intermediate portion 1, a top portion 2 and a bottom portion 3. The intermediate portion merges into the top portion and gradually increases in diameter from its lower to its upper terminus. The top portion 2 gradually increases in diameter from its lower to its upper terminus and is of greater diameter throughout than the diameter of the intermediate portion 1. The bottom portion 3 gradually increases in diameter from its upper to its lower terminus and the lower terminus of the bottom portion 3 is flared, as at 4. The lower terminus of the intermediate portion 1 merges into the upper terminus of the bottom portion 3. The inner face of the bottom portion 3, or rather that portion of the inner face of the bottom portion 3 which extends upwardly from the flaring end 4 of said bottom portion 3, provides what may be termed a tapered valve seat 5. The upper terminus of the top portion 2 is beaded as at 6 and provided with a reinforcing member 7.

Hinged to the top portion 2, as at 8, is a dome-shaped cover 9, having a reinforced edge 10 which when the cover 9 is closed, seats on the bead 6 of the top portion 6. Carried by the top portion 2 and having one end, as at 11, bearing against the top portion 2, and its other end as at 12, bearing against the inner face of the cover 9, is a coiled spring 13, the function of which is to normally maintain the cover 9 in open position, as illustrated in Figure 3. Secured to the outer face of the cover 9 is a handle member 14, which has projecting therefrom a spring latch 15, which is adapted to overlap the bead 6, for the purpose of detachably connecting the cover 9 in closed position, against the action of the spring 13. When the latch 15 is disconnected from the top portion 2 of the body portion of the receptacle, the spring 13 will automatically open the cover 9 and maintain the latter in an upright position as shown in Figure 3.

Formed integral with the intermediate portion 1 of the body portion of the cuspidor, and projecting laterally therefrom, is a hanger arm 16, through which extend suitable hold-fast devices 17 for the purpose

of securing the cuspidor to the body of the car or coach, as indicated at 18. The hanger arm 16 may be formed integral with the intermediate portion 1 or fixedly secured there-
5 with in any suitable manner.

Projecting laterally from the intermediate portion 1, on that side thereof opposite the side to which the hanger arm 16 is connected, is a combined guide and keeper 19, 10 formed with an opening for the passage of a spring controlled actuating rod 20.

Formed integral with the intermediate portion 1, below the guide or keeper 19, is a laterally extending housing 21, having its 15 top and bottom apertured, as at 23 for the passage of the rod 20, and said rod 20 not only depends below the housing 22, but below the bottom portion 3 of the body portion of the cuspidor. Fixedly secured to 20 that portion of the rod 20 which extends through the housing 22, is a collar 25, and interposed between said collar 25 and the bottom of the housing 22, as well as surrounding rod 20, is a coiled spring 26, the 25 function of which is to normally maintain the rod 20 in an elevated position.

The rod 20, at its top, has a handle member 27 connected therewith, and said rod 20 at its lower end is formed with an angle-shaped extension consisting of a horizontal leg 28 and a vertical leg 29. The extension of the rod 20 is permanently arranged below the bottom of the body portion of the cuspidor.

35 Fixedly secured to the vertical leg 29, of the angle-shaped extension of the rod 20, is what may be termed the shiftable bottom of the receptacle, and which is of valvular contour and comprises a tapered body portion 30 and a conoidal-shaped extension 31 at the top thereof. The body portion 30 is of a diameter as to snugly engage the valve seat 5 for the purpose of closing the lower end of the body portion of the cuspidor to prevent leakage and said shiftable bottom is normally maintained in closed position due to the expansion of the spring 26 and which acts against the collar 25 for the purpose of maintaining the rod 20 in its upper position, such as shown in Figure 2. The flared end 4 of the bottom 3 of the body portion of the cuspidor provides for the convenient entry of the shiftable bottom when the latter is moved to closing position through the action of the spring 26.

When the rod 20 is moved downwardly, the spring 26 is compressed, and the shiftable bottom is carried with the rod 20, whereby the lower end of the body portion of the cuspidor will be opened and the contents 60 discharged. When the shiftable bottom is lowered it can be swung to one side if desired so that it will not interfere with the discharge of the contents of the cuspidor. If desired, the cuspidor can be provided 65 with a body of water 32.

From the foregoing description taken in connection with the accompanying drawings a cuspidor is set up which is thoroughly efficient for use in connection with railway 70 coaches or street cars, or for other purposes for which it is found applicable, and provides for the discharge of the contents of the cuspidor without disconnecting the cuspidor from its set position, and although the 75 preferred embodiment of the invention is as illustrated and described, yet it is to be understood that changes in the details of construction can be had which will fall within the light of the invention as claimed. 80

What I claim is:—

A cuspidor comprising a hollow body formed of an intermediate, a top and a bottom portion, each of said portions being tapered, the taper of the bottom portion extending in opposite direction with respect to the taper of the intermediate portion, said bottom portion having a part of its inner face constituting a valve seat, a shiftable bottom of valvular type normally extending 85 in said bottom portion and engaging said seat for closing said body, said shiftable bottom including a tapered body portion provided at its top with a conoidal-shaped extension, a spring controlled manually shifted 90 rod slidably connected with said body and provided at its lower end with an angle-shaped extension having one of its legs fixedly secured to lower face of said shiftable bottom, a laterally extending combined guide 95 and keeper carried by said body and through which said rod extends, and a laterally extending housing projecting from said body and through which said rod extends, said housing inclosing the controlling spring for 100 said rod.

In testimony whereof, I affix my signature hereto.

JOHN STRAUB.
